UNITED STATES PATENT OFFICE.

TAPLEY W. YOUNG, OF WASHINGTON, DISTRICT OF COLUMBIA, ASSIGNOR
OF ONE-HALF TO JOHN C. McGOWAN, OF SAME PLACE.

CLOSURE FOR CANS AND OTHER VESSELS.

SPECIFICATION forming part of Letters Patent No. 340,650, dated April 27, 1886.

Application filed September 4, 1885. Serial No. 176,118. (No model.)

To all whom it may concern:

Be it known that I, TAPLEY W. YOUNG, a citizen of the United States, and a resident of Washington, in the District of Columbia, have 5 invented certain new and useful Improvements in Closures for Cans and other Vessels; and I do hereby declare that the following is a full, clear, and exact description of the invention, which will enable others skilled in the art 10 to which it appertains to make and use the same, reference being had to the accompanying drawings, which form a part of this specification.

This invention relates to cans and other vessels for containing fruits, meats, or other articles of food, or any other articles which are to be preserved by being hermetically sealed; and the invention has for its object to provide 15 means whereby the hermetic sealing may be 20 most thoroughly and efficiently carried out easily and at a moderate expense.

With these ends in view the invention consists in certain improvements in the construction of the cans or vessels and the sealing attachments, which will be hereinafter fully described, and particularly pointed out in the 25 claims.

In the drawings hereto annexed, Figure 1 is a vertical sectional view of a can, showing the 30 same ready to be sealed. Fig. 2 is a vertical sectional view of a can having the sealing top applied thereto. Fig. 3 is a vertical sectional view of a can, showing the same sealed; and Fig. 4 is a vertical sectional view illustrating 35 a modification of the invention.

The same letters refer to the same parts in all the figures.

A in the drawings designates a fruit or meat can of ordinary construction, the top of which, 40 B, is provided with the opening C, through which the contents may be placed in the can.

D designates a funnel-shaped flange extending 45 downwardly into the can from the edge of the opening C, said funnel or flange being suitably soldered or secured to the top B of the can. The funnel or flange D, which may be struck up or spun from sheet metal or other suitable material or be otherwise suitably constructed, is provided at the lower edge of its 50 neck or spout E with an annular inwardly

and upwardly turned rim, F, the purpose of which will be presently set forth. The said neck E is also provided with an inwardly-extending annular corrugation, F'.

G designates a bulging or concavo-convex 55 disk, which is to be stamped or otherwise formed of any suitable ductile sheet metal, and which is provided at its edge with an annular rim or flange, H, by means of which it may be soldered to the top B of the can directly 60 over the opening C, which is thereby closed. It will also be seen that the said disk is thus made to register with and cover the funnel D, which has been described above. To the under concave side of the said disk is cemented 65 or otherwise suitably attached a stopper, I, which is preferably made of rubber, although a good quality of cork or other appropriate material might be substituted. This stopper should be of such a size as to fit nicely in the 70 neck or spout E of the funnel D, with which, when the disk G is placed in position, it registers, as will be seen in Fig. 2 of the drawings.

When the disk G has been placed in position, and attached to the cover of the can, the next step in the process will be to exhaust the air from the can. This operation may be performed in any suitable well-known manner, the opening for the escape of the air being 80 formed either as indicated at letter J in the drawings in the concavo-convex disk G, or, when preferred, in the top B of the can. The air having been exhausted, the can is to be subjected to pressure, whereby the disk G shall 85 be flattened, as will be seen in Fig. 3 of the drawings, or even inverted, as indicated in dotted lines in the same figure. By this operation the cork or stopper attached to the under side of the said disk G will be forced 90 into its seat in the neck E of the funnel D, where it fits tightly, and its lower end will be pressed against the upturned edge of the rim F, which, together with the flange F', will form additional seats for the said stopper, 95 which latter will thus form an absolutely airtight plug.

Although the aperture through which the air is exhausted from the can may, as before stated, be made in the top B of the can, it is 100

much more desirable to locate it in the concavo-convex disk G, as shown at J, as it will be seen that when the stopper I has been forced down, so as to hermetically close the opening 5 in the lower end of the funnel D, it will of course be impossible for any air to reach and escape through the opening J, which renders it unnecessary to close the said opening by solder or otherwise, which would be necessary 10 if the exhaust-aperture were made in the top B of the can.

It will be seen that the tops of cans that have been equipped with my invention may be readily removed in the usual manner by 15 means of a cutter or can-opener of ordinary construction. This sealing for a can or other vessel renders the same absolutely air-tight, inasmuch as the pressure of the external air against the outside of the ductile disk G will 20 tend to force the same inward, thus forcing the stopper I tightly against its seat.

The process of sealing the cans equipped with my improvement is simple and easily carried out, while the expense is moderate.

25 In Fig. 4 of the drawings hereto annexed I have shown a modification of my invention, whereby it may be applied to jars or vessels made of glass or earthenware or the like.

J designates the upper end of the jar or vessel, which has an exteriorly screw-threaded neck, K, on the upper edge of which may be placed a gasket or washer, L, of rubber or other suitable material.

M designates a cover, which is provided 35 with a screw-threaded rim or flange, N, by which it may be screwed into position upon the screw-threaded neck, and be tightened down against the gasket or washer, so as to make an air-tight joint. The cover M, which 40 is constructed of metal, is provided with the downwardly-extending funnel-shaped flange D', having the neck or spout E', at the lower edge of which is formed the inwardly and upwardly turned corrugation F'. The said funnel may be formed in one piece with, or it 45 may, if preferred, be suitably attached to, the cover M.

G' designates the concavo-convex disk, having the stopper I' attached to its under side. 50 This disk is attached to the cover M in the same manner as the disk G is attached to the top of can A, as above described, after which the air is exhausted, and the disk G' subjected to pressure, so as to force the stopper to its seat.

Having thus described my invention, I claim 55 and desire to secure by Letters Patent of the United States—

1. The combination, with a preserving-vessel, the top of which is provided with an opening, of a funnel-shaped flange extending downwardly from the edge of the said opening and having at the lower edge of its neck or spout an inwardly and upwardly turned rim or flange, substantially as and for the purpose herein shown and specified. 65

2. The combination, with a preserving-vessel, the top of which is provided with an opening, of a funnel-shaped flange extending downwardly from the edge of the said opening, and a concavo-convex disk of ductile metal secured to the top of the can over the opening in the same, and having a suitable stopper attached to its under concave side and registering with the neck of the funnel, substantially as and for the purpose herein set forth. 70

3. The combination, with a preserving-vessel, the top of which is provided with an opening, of a funnel-shaped flange extending downwardly from the edge of the said opening, and having at the lower edge of its neck or spout 80 an inwardly and upwardly turned rim or flange, and a concavo-convex disk of ductile metal secured to the top of the can over the opening in the same, and having a suitable stopper attached to its under concave side, 85 substantially as and for the purpose herein set forth. 75

4. The combination, with a preserving-vessel having a screw-threaded neck and a washer or gasket placed thereon, of a detachable cover 90 constructed with a downwardly-extending screw-threaded flange, said cover being also constructed or provided with a downwardly-extending funnel having an inwardly and upwardly turned flange at the lower edge of its 95 neck, and a concavo-convex disk of ductile metal secured to the upper side of the said cover over the funnel of the same, and having a suitable stopper attached to its under concave side, substantially as and for the purpose herein set forth. 100

In testimony that I claim the foregoing as my own I have hereunto affixed my signature in presence of two witnesses.

TAPLEY W. YOUNG.
